UNITED STATES PATENT OFFICE.

JOHN N. REYNOLDS, OF GREENWICH, CONNECTICUT, ASSIGNOR TO WESTERN ELECTRIC COMPANY, OF NEW YORK, N. Y., A CORPORATION OF ILLINOIS.

SENDING DEVICE.

1,147,437.

Specification of Letters Patent.

Patented July 20, 1915.

Application filed February 12, 1915. Serial No. 7,727.

To all whom it may concern:

Be it known that I, JOHN NEWBERRY REYNOLDS, a citizen of the United States, residing at Greenwich, in the county of 5 Fairfield and State of Connecticut, have invented certain new and useful Improvements in Sending Devices, of which the following is a full, clear, concise, and exact description.

10 This invention relates to sending devices and is particularly designed for use at a telephone substation in conjunction with a register sender device at the central station, although its use is not limited to systems 15 employing central station register senders.

The object of this invention resides in the provision of means whereby the desired number of impulses may be transmitted with accuracy and with great rapidity.

20 In the structure disclosed in this application, each time one of the operating members is actuated, the sender goes through a certain cycle of operations whereby it tends to transmit a certain definite number of 25 impulses, but the number of impulses which are effective, that is, the number which pass over the line circuit, is governed by the operating member actuated which interrupts the sender circuit to certain of the sending contacts.

30 Referring to the drawings—Figure 1 is a top or plan view of the device with the cover partly removed; Fig. 2 is a view substantially on the line 2—2 of Fig. 1; Fig. 3 is 35 a diagrammatic view illustrating the sending contacts and the brush or wiper; Fig. 4 is a section substantially on the line 4—4 of Fig. 2; and Fig. 5 is a view similar to Fig. 4 showing the operating mechanism in a 40 slightly different position.

Briefly described, the device herein disclosed operates as follows: Whenever one of the keys 1 is depressed the spring 2 is tensioned to drive, by means of a suitable train 45 of gears, the shaft 3 through a complete revolution. Carried at the upper end of the shaft 3 is the interrupter brush 4, one end of which trails on the continuous plate 5. (Figs. 1 and 3) connected to one side of the 50 line, and the other end of which traverses a series of ten (0 to 9) contacts 6. Each of these contacts is electrically connected to a contact spring 7. The depression of a key in addition to winding up the spring 2, 55 causes the contact spring 7 corresponding

thereto to break connection with the next succeeding spring 7 (see Fig. 3). Thus, while the brush 4 in going through a cycle of operations traverses all the contacts 6, only so many of the contacts will be effective to 60 transmit impulses over the line as precede the point at which an interruption occurs in the series circuit through the several springs 7.

Now describing the device in detail, the 65 finger-pieces 1 are carried by arms 8 projecting from the pivot members 9. The bearings for the pivot members 9 are formed by notches in the upper edges of the casing 10 and in brackets 11 secured thereto, the top 70 of the bearings being provided by the cover or cap plate 12 which is secured to the casing 10 by means of lugs 13 and screws therethrough, as shown in Fig. 2.

Secured in any desired manner to the pivot 75 member 9 of each key or actuating member, is an arm or bracket 36 to which is insulatively secured a spring 7. When the sender is in its normal condition, the springs 7 occupy relative positions such that each, 80 with the exception of those at each end, are engaged by the preceding spring and in turn engage the one following. This arrangement will be readily understood from an inspection of Fig. 3. Projecting from each 85 spring 7 is a contact 6 arranged substantially in alignment with the pivot 9, so that when said pivot is rotated, the contact 6, carried thereby, is not displaced, but as before described, when the pivot 9 is rotated by the depression of an actuating member 1, the spring 7 carried thereby is tilted so that it breaks connection with the following 90 spring 7. It does not, however, break connection with the preceding spring due to 95 the flexibility of said spring and the fact that the left end (Fig. 3) of the actuated member 7 is shorter than the right end and therefore moves a less distance.

Each of the pivot members 9 is provided 100 at its inner end with a laterally and downwardly projecting portion 14. The spring 15 secured at one end to the arm 14' and at its other end to a lug 16, carried by the casing 10, serves to normally maintain the key 105 in its uppermost position. Secured to the casing 10, about midway of the height thereof and projecting parallel to the bottom of said casing, is a supporting member 17 through which extends the shaft 3, the other 110

end of the shaft being journaled in the bottom plate of the casing 10. Rotatably mounted on the shaft 3 is a spider 18 having projecting fingers 19, one for each key. Now, when one of the keys 1 are depressed, the downwardly projecting member 14 engages its respective finger 19 and causes the spider 18 to be rotated a fraction of a revolution. Also rotatably mounted on the shaft 3, adjacent to the spider 18, is a ratchet wheel 20 engaged by the pawl 21 pivotally secured to the lower side of the spider 18. Mounted on a sleeve or collar about the shaft 3 is a spring 2; one end of which is fixed to the ratchet wheel 20, the other end being secured to the gear 22. The gear 22 loose on shaft 3, meshes with the pinion 23, Fig. 4, mounted on the pivot screw 24 which projects from the bottom of the casing 10. Integral with the pinion 23 is a gear 25, which in turn meshes with the pinion 26 fixed to the shaft 3. Thus, when the spider 18 is rotated, it causes, through pawl 21, the rotation of the ratchet 20 and this in turn tensions the spring 2 of the motor. The spring 2 causes the gear 22 to rotate, which rotation is transmitted through pinion 23, gear 25 and pinion 26 to the shaft 3 to cause the sender brush or wiper 4 to make one complete revolution.

Fixed to the shaft 3, adjacent the bottom of casing 10, is a plate 27 having a projection 28 which is normally engaged by the hook-like member 29 (Fig. 4) pivotally mounted on the pin 30. Fixed to the member 29, by means of the collar 31, is an actuating member 32, the purpose of which will presently appear. Coiled about the collar 31 is a spring 33, one end of which is secured to the stud 34 projecting from the bottom of the casing 10, the other end being secured to the member 29. This spring tends to rotate the member 29 in an anti-clockwise direction. When the sender is in its normal position, the hook of member 29 is in engagement with the radially extending surface of the projection 28. When, however, one of the keys is actuated and the spider 18 is rotated, the finger 19 (Fig. 5), engages the member 32 to rotate it, together with the hook 29, in a clockwise direction. This releases the plate 27 which, it is remembered is secured to the shaft 3 and allows the rotation of the shaft and parts carried thereby. As the hook 29 is moved outward, the right angularly extending portion 35, integral therewith, is forced inward and rides on the periphery of the plate 27 until it is engaged by the radially extending surface of the projection 28, which stops the movement of the wiper brush. This happens during the brief space of time the key is depressed. Upon the release of the key, the spider returns to its normal position, as shown in Fig. 4. The member 32 is released and allows the spring

33 to rotate the member 29 to move 35 out of engagement with the projection 28. The plate 27 thereupon advances a short distance until it engages the hook 29, in which position it is maintained until another operating member is actuated. Upon the return or clockwise rotation of the spider 18 the pawl 21 carried thereby rides over the teeth of the ratchet 20, the rotation of the ratchet wheel 20 being prevented by means of the pawl 37, pivotally mounted on the collar 31 and normally held in engagement with the ratchet wheel by means of the spring 38, one end of which is fixed to a projecting portion of the pawl 37, the other end being secured to a lug 39 carried by the casing 10. During the above described operation, the shaft 3 has made a complete revolution and the brush 4 has made engagement with each of the sending or impulse contacts 6. This movement of the brush 4 has taken place while the actuating member is still depressed. Therefore, one of the springs 7 will be in a position similar to that occupied by the fourth spring in Fig. 3, and if this corresponds to the key operated only four impulses will be transmitted over the line.

As it is obvious that many modifications may be made in this invention without departing from the spirit thereof, the invention should be limited only by the scope of the claims.

What I claim is:

1. In a controlling apparatus, a line, an impulse device associated therewith, devices for actuating said impulse device, means actuated upon the operation of any one of said actuating devices for causing said impulse device to make a certain definite number of electrical contacts, and means governed by the operated actuating device for determining the number of said electrical contacts which will be effective to alter the electrical condition of said line.

2. In a controlling apparatus, a line, an impulse device connected thereto, devices for actuating said impulse device, a motor, means whereby the operation of any one of said devices will tension said motor to drive said impulse device through a definite cycle of operations which will cause it to make certain electrical contacts, and means governed by the operated actuating device for determining the number of said electrical contacts which will be effective to alter the electrical condition of said line.

3. In a controlling apparatus, a series of actuating devices, a series of normally electrically connected impulse contacts, a wiper, means operated upon the actuation of one of said devices for causing said wiper to traverse the contacts of said series, and means also operated by such actuation for interrupting the electrical connection to certain of said contacts.

4. In a controlling apparatus, a series of actuating devices, a series of normally electrically connected impulse contacts, a wiper, a motor, means operated upon the actuation 5 of any one of said devices for tensioning said motor whereby said wiper is caused to traverse the contacts of said series, and means also operated by such actuation for interrupting the electrical connection to certain of said series of contacts.

5. In a controlling apparatus, a series of actuating devices, a series of normally electrically connected impulse contacts corresponding thereto, a conducting strip, a 15 wiper, means operated upon the actuation of any one of said devices for causing said wiper to successively connect said contacts to said conducting strip, and means also operated by such actuation for interrupting the electrical connection between certain contacts of said series.

6. In a controlling apparatus, a series of actuating devices, a series of electrically connected impulse contacts, a wiper, a rotatable 25 disk, means operated upon the actuation of any one of said devices for causing rotation of said disk, a motor device tensioned by such rotation, means controlled by said motor device for causing said wiper to success-

sively engage each of said impulse contacts, 30 and means dependent upon the operated actuating device for interrupting the electrical connection between certain contacts of said series.

7. In a controlling apparatus, a series of 35 actuating devices, a series of impulse contacts, a wiper, a shaft upon which said wiper is mounted, a movable plate, means whereby the operation of any one of said actuating devices will cause a movement of 40 said plate, a motor device, means whereby the movement of said plate will tension said motor device whereby said shaft is caused to perform one complete revolution, a series of 45 normally electrically connected contacts traversed by said brush during such revolution, and means controlled by the operated actuating device for interrupting the electrical connection between certain contacts of said series.

In witness whereof, I hereunto subscribe my name this 11th day of February A. D., 1915.

JOHN N. REYNOLDS.
